UNITED STATES PATENT OFFICE.

FRANK JUDSON JEWELL, OF ROME, NEW YORK, ASSIGNOR TO FRANK JUDSON JEWELL
AND NELSON ADAMS, BOTH OF ROME, NEW YORK, TRADING UNDER THE FIRM
NAME OF BETSON PLASTIC FIRE BRICK CO.

METHOD OF FORMING BAFFLE-WALLS FOR BOILERS.

1,288,014.

Specification of Letters Patent. Patented Dec. 17, 1918.

Application filed October 17, 1918. Serial No. 258,662.

To all whom it may concern:

Be it known that I, FRANK JUDSON JEWELL, a citizen of the United States of America, and resident of Rome, in the county of Oneida and State of New York, have invented a certain new and useful Improvement in Methods of Forming Baffle-Walls for Boilers, of which the following is a true and exact description, reference being had 10 to the accompanying drawings, which form a part hereof.

My invention relates to the building up of baffle walls in tubular boilers and has for its object to provide a method for building 15 up among the tubes of such boilers a strong impervious baffle wall formed of fire brick molded into the place where it is to be used.

Broadly speaking, my invention consists in building up among the tubes of the boiler 20 a mold or form shaped and adapted to contain and form the fire brick baffle wall and then charge into such mold or form successive portions of unburned and plastic fire brick material, then tamping such successive portions to force the plastic material 25 into contact with the sides of the mold and the tubes and into coherence with previously inserted portions until the mold is filled, and finally subjecting the baffle wall thus built to 30 a high temperature to convert the material into fire brick.

By preference I form any mold wall, which is not intended to form the permanent element of the baffle, of wood and leave 35 it in place until the heat and flame, applied for hardening the fire brick, burns it away, and in the case of transverse baffle walls I form the wooden mold wall of transversely running wooden slats, one set running be- 40 tween the tubes in one direction and another set running between the tubes in another direction and crossing so as to form a grid.

Reference being now had to the drawings 45 in which my invention is illustrated and in which—

Figure 1 is a perspective view illustrating the construction of a transverse baffle wall across the tubes of a tubular boiler, 50 and

Fig. 2 is a similar perspective view illustrating the construction of longitudinally running baffle walls among the tubes of the boiler.

A, Fig. 1, indicates a wall extending up 55 below the tubes, as, for instance, is the case with the back wall of the fire box, BB, etc., are the boiler tubes, C is a baffle wall formed of an iron plate or plates, with the tubes passing through perforations in such plates 60 in the usual manner. DD, etc., are wooden slats running transversely and obliquely between the tubes B, D', D', etc., are similar wooden slats running transversely and obliquely in the other direction between the 65 tubes and lapping on and forming a wall with the slats D. The wall made up of the slats D and D' lies parallel with the opposite wall made up of the plate or plates indicated at C, with the space between the two 70 walls of the breadth or thickness which it is intended that the fire brick of the baffle wall should have. E is the plastic unburned fire brick material which I insert between the two walls of the mold through the top opening 75 in successive and comparatively small portions, each of which is tamped down by a tamping iron such as indicated at F, so as to force the plastic material to fill the mold space and to form a close contact with all 80 sides of the tubes, and so also as to insure the adhesion of the different successive portions of plastic material with each other.

Referring next to Fig. 2, which illustrates the formation of baffle walls running parallel with the tubes, the mold walls are made up of wooden slats or beams indicated at d and d'. The baffle walls indicated in this figure at E' and E'' are formed of the same material and in the same way as described 90 as to Fig. 1.

When the molds have been entirely filled with the coherent masses or layers of plastic fire brick material applied as described a fire is built in the fire box of the boiler for the 95 purpose of heating and converting the plastic fire brick material into fire brick and burning away such wooden mold walls as have been used in its manufacture. The temperature regulation of such a fire should, 100 of course, be governed in accordance with the well known conditions applicable to the proper heating of the material to be converted into fire brick.

The baffle walls, formed as above de- 105 scribed, are strong, coherent and tight, and thoroughly well adapted for either purpose.

Having now described my invention, what

I claim as new and desire to secure by Letters Patent, is:

1. The method of forming baffle walls of refractory material for tubular boilers, which consists in inclosing a space to be filled by such material by walls, charging repeated portions of plastic unburned firebrick material into said space and tamping it to insure its filling its portion of the space and its union with previously tamped portions and finally subjecting the completed baffle wall to heat to give it hardness and permanency.
2. The method of forming baffle walls of refractory material for tubular boilers, which consists in inclosing a space to be filled by such material by walls, in whole or in part formed of wood, charging repeated portions of plastic unburned fire brick material into said space and tamping it to insure its filling its portion of the space and its union with previously tamped portions and finally subjecting the completed baffle wall to heat to give it hardness and permanency, and to burn out the wooden wall portions.
3. The method of forming transverse baffles of refractory material in tubular boilers,

which consists in inclosing a space to be occupied by such baffle wall between walls intersected by the boiler tubes, charging repeated portions of unburned plastic fire brick material into said space and tamping said portions to cause it to fill the space around the tubes and between the walls and to cohere with previously charged portions and subjecting the completed baffle wall to heat to give it hardness and permanency.

4. The method of forming transverse baffles of refractory material in tubular boilers, which consists in inclosing a space to be occupied by such baffle wall between walls intersected by the boiler tubes, and consisting in whole or in part of wooden slats inserted between the tubes, charging repeated portions of unburned plastic fire brick material into said space and tamping said portions to cause it to fill the space around the tubes and between the walls and to cohere with previously charged portions and subjecting the completed baffle wall to heat to give it hardness and permanency and burn away the wooden slats.

FRANK JUDSON JEWELL.
